ARTICULATED TRUSS

Henry L. Hoffmann, Minneapolis, Minn.

Application June 28, 1950, Serial No. 170,884

2 Claims. (Cl. 128—103)

1

This invention is related to a truss, and more particularly a cross body type of truss. Trusses are in wide general use and special skill is required to properly fit or adjust the ordinary type of truss. Subsequent to the initial fitting, adjustments are required from time to time to adapt the truss to changing body contours which result from fluctuations in weight. Because of the high degree of skill required to properly fit or adjust a truss, the wearer must seek expert help to properly fit or adjust his truss. For this reason it is difficult to distribute trusses through retail outlets. A retail outlet is generally not in a position to provide the expert assistance required for a proper fitting.

One form of truss used in large numbers is made of a single band of metal, such as spring steel, which is bent to conform generally to the shape of a body to partially embrace the same as is designed to have the maximum pressure applied to the pad which overlies the hernial opening. To fit an individual wearer, the spring band must be sprung or bent and a compensating adjustment is required elsewhere in the band. It is in springing the band that great skill is required and a precise fitting is required to secure beneficial results from the use of the truss.

It is an object of this invention to provide a truss made of articulated construction which can be readily adapted to fit the body of a wearer and which does not require the use of special skill to make a proper fitting.

It is another object of this invention to provide a truss having a plurality of pivotally connected sections whereby a wearer can readily adapt his own truss to fit his body comfortably and to provide him with maximum benefits from its use.

It is more specifically an object of this invention to provide a truss which comprises a band having a plurality of sections adapted to have their adjacent ends pivotally joined together, means provided to permit relative swinging or pivotal adjustment of said sections and to hold the same securely in a given position.

It is a still more specific object of this invention to provide a truss having in combination, a band having a plurality of intermediate sections, and a pair of end sections, said sections being pivotally connected at their respective adjacent ends, the end portions of said sections having parts of reduced thickness, said parts having inter-engaging surfaces, means provided to clamp said engaging surfaces in rigid position to permit lateral adjustment of the same, and

means for rigidly connecting the end sections to the intermediate sections.

Other objects and advantages of the invention will be apparent from the following description made in connection with the accompanying drawings in which like reference characters refer to similar parts throughout the several views and in which:

- Fig. 1 is a plan view of applicant's device;
- 10 Fig. 2 is a view in front elevation taken on line 2—2 of Fig. 1 in the direction indicated by the arrows;
- Fig. 3 is a view in vertical section of a joint shown on an enlarged scale;
- 15 Fig. 4 is a view taken on line 4—4 of Fig. 2 with some parts shown in horizontal section;
- Fig. 5 is a bottom plan view of the front or hernial pad with dotted lines showing a change in position;
- 20 Fig. 6 is a bottom plan view with some parts broken away and some parts in section of a modification of a rear pad;
- Fig. 7 is a view in vertical section taken on line 7—7 of Fig. 6 in the direction as indicated by the arrows with some parts shown in a different position by dotted lines;
- 25 Fig. 8 is a view in vertical section showing a modification of the band shown in Fig. 1; and
- Fig. 9 is a view in side elevation of the arm shown in Fig. 6.
- Referring to the drawings, a band 10 is shown. Said band is substantially flat and substantially rectangular in vertical cross section and is made of a flexible resilient material designed to bring a high degree of pressure to bear upon its end portions. In the embodiment of the invention as illustrated, a spring steel band is used. Said band 10 has in combination front and rear end sections 10a and 10b respectively and a plurality of intermediate sections, such as 10c, 10d, 10e and 10f. Said sections are of different lengths. A front or hernial pad 11 and a rear pad 12 are provided and are removably secured to the outer ends respectively of sections 10a and 10b. Pad 11 is secured by screws 15 and 16 and pad 12 is secured by screw 17.

Pad 11 is egg-shaped in plan and comprises a backing portion 11a made of a stiffened sheet material, a facing portion 11b made of resilient material of substantial thickness and a covering 11c made of a soft material overlying said facing portion and being secured to said backing portion. Centered in said backing portion is a threaded aperture 11d and spaced equi-distant

therefrom in said backing portion are threaded apertures 11e and 11f.

Pad 12 is of a general elliptical shape in plan and comprises a backing portion 12a made of a stiffened sheet material and a relatively thin padded facing portion 12b secured thereto. Centered in said backing portion is a threaded aperture 12c adapted to receive screw 17. In the embodiment of the invention as illustrated said backing members 11a and 12a are made of metal.

Pads 11 and 12 as described above are of an ordinary variety and are in common use.

As shown in Figs. 2 and 3, the inter-engaging end portions of adjacent sections are made of a reduced thickness, such as 10g and 10i. Said end portions are circularly shaped, as shown in Fig. 4 and thus form cylindrical lugs respectively integral with said sections. Said inter-engaging end portions are respectively provided with bores to be presently described having aligned axes extending vertically and transversely of said band 10. The end portion 10g has a bore 10h which is interiorly threaded and end portion 10i has a bore 10j which has a smooth interior. The upper portion of bore 10j has a countersunk recess 10k. When said end portions are in inter-engagement, said bores are in direct alignment. The engaging surfaces of said inter-engaging end portions have radially extending circumferentially spaced corrugations 10l, as shown in Fig. 4. A locking member or screw 14 is provided having a countersunk head 14a and a slot 14b placed in said head and adapted to receive a screw driver or similar tool for rotating the same. When disposed in bores 10h and 10j, said screw or locking member is securely held in said threaded portion 10h. The head portion 14a is received in recess 10k and rests therein flush with the top surface of said recess.

In operation, locking members 14 are loosened slightly in each of the inter-engaging end portions. The truss is then positioned to embrace the body. The hernial pad is placed directly over the hernial opening and the first or front section is positioned accordingly. As shown in Fig. 5, said hernial pad may be positioned for use on either the right or left front of the body and either aperture 11e or 11f is used accordingly. Then the locking members are tightened in respective order starting with the front or first locking member as each respective section is positioned to conform to the contours of the body of the wearer. Whatever degree of pressure is required can be brought to bear upon pad 12 which overlies the hernial opening. Band 10 in comprising sections of different lengths is particularly adapted to readily accommodate changing body contours and the wearer can properly make substantial or slight adjustments so that a precise fitting can be had at all times. The inter-engaging ends being circular in horizontal section provide for adequate pivotal adjustment. Adjustments are thus easily made as weight fluctuations cause changes in the body contours. The corrugations in the engaging surfaces provide a positive locked or clamped position when said locking members 14 are tightened. When the short sections, such as 10d and 10e, are in locked position, the larger sections, such as 10a, together with 10c and 10b, together with 10f, respectively, act as cantilevers. Said longer sections provide considerable spring or tension which is focused at their respective end portions where it is most required.

The fact that adjustments are readily made permits the retail sale of applicant's trusses through drugstores and similar outlets on a satisfactory basis because the wearer can fit his own truss properly. The ordinary type of truss requires a particular skill to be fitted properly and to have subsequent adjustments made. Hence this item is not satisfactorily sold through a store but is properly sold by an expert fitter. This need of an expert for a proper fitting increases the cost of a truss substantially and also restricts the scope of its distribution considerably.

A modified form of a pad and mounting is shown in Figs. 6 and 7. A back pad 18 is shown which may be substituted for pad 12. Pad 18 comprises a cushion portion 18a which is of cylindrical shape and is made of resilient material of substantial thickness. A pair of thin circular metal plates 18b overlie the cushion portion 18a centrally thereof each having a semi-cylindrical channel 18c extending diametrically thereacross, said channels mating to form the cylindrical passage 18c. A member 18e made of a strong flexible sheet material is disposed over plates 18b and is secured to said cushion portion 18a by an adhesive. Another plate 18h overlies said member 18e centrally thereof and is secured to plates 18b by a pair of spaced screws 15. Disposed over the face portion of said pad is a cover 19 made of soft sheet material and is secured thereabout by a draw string 19a.

An arm 20 shown as a round rod is disposed in passage 18c and is rotatably secured therein by a spring clip 21 extending about the arm 20 in a groove 20a therein and having end portions extending through a hole 18d in one of the plates 18b. Said arm has an end portion 20b extending at right angles thereto. A section of the band 10, such as 10n, is provided which in use with pad 18 is substituted for band section 10b and is secured in like manner to the adjacent section 10f. The outer end of section 10n is provided with an enlarged portion 10p and extending vertically therethrough is an interiorly threaded bore 10q. Adapted to be secured in said bore is said end portion 20a. Thus pad 18 is rotatable transversely of said band portion and it provides a comfortable adjustment in being placed against the back of the wearer.

Referring to Fig. 8, band 10 is shown in vertical cross section and placed thereabout is a covering 22. Said covering is made of a resilient flexible sheet material having durable wearing qualities and being impervious to body acids and perspiration. In the embodiment of the invention as illustrated, a plastic material is used. Said covering when used is placed about the respective sections of band 10 and is made to accommodate the inter-engagement of adjacent end portions.

Thus it is seen that I have provided a truss of novel and efficient articulated structure which will give a wearer the maximum benefits from its use at all times as it permits the wearer to make proper adjustment whenever the same is required.

It will of course be understood that various changes may be made in the form, details, arrangement and proportions of the parts, without departing from the scope of applicant's invention, which generally stated, consists in a device capable of carrying out the objects above set forth, in the parts and combinations of parts

disclosed and defined in the appended claims.

What is claimed is:

1. A truss comprising a band to be placed about the body of a person, said band having a plurality of sections, said sections respectively having integral therewith end portions formed as lugs having a thickness less than the width of said band, said lug portions adapted to overlap, screws respectively disposed in said overlapping portions to pivotally connect said sections and 10 pads respectively secured to the remote ends of said band.

2. A truss comprising a band to be placed about the body of a person, said band having a plurality of sections, cylindrical lugs formed at adjacent ends of said sections respectively integral with said sections and having a thickness less than the width of said band, said lugs adapted 15

to overlap and having serrated mating surfaces, a screw disposed in said overlapping lugs to pivotally connect said sections, and pads respectively secured to the remote ends of said band. 5
